The ornamental design for a label and display card holder, as shown and described.

DESCRIPTION

FIG. 1 is a perspective view of a label and display card holder showing my new design;

FIG. 2 is a right side elevational view thereof, with a left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view thereof with the holder being flexed into an open condition and mounted to the front of an associated shelf; and,

FIG. 8 is a side elevational view thereof with the holder holding both an associated sign and an associated label and being mounted to an associated shelf.

The components illustrated in broken lines in FIGS. 7 and 8 form no part of the claimed design.
